UNITED STATES PATENT OFFICE.

JOHN WILKS, OF PURLEY, ENGLAND.

TOY FIGURE.

1,183,149.

Specification of Letters Patent.

Patented May 16, 1916.

Application filed July 6, 1915. Serial No. 38,267.

To all whom it may concern:

Be it known that I, JOHN WILKS, a subject of the King of Great Britain, residing at Dunningley, Great Woodcote Park, Purley, 5 in the county of Surrey, England, leather merchant, have invented certain new and useful Improvements in or Connected with Toy Figures, of which the following is a specification, reference being had to the drawings hereunto annexed, and to the figures and letters marked thereon—that is to say—

This invention relates to improvements in or connected with toy figures.

Heretofore, numerous toy figures have 15 been produced but these have in general possessed the inherent disadvantage of instability, the more so the lighter and larger they have been made, and, in fact, what may be designated flat or plane figures,—made 20 of cardboard, then wood and the like—have been so constructed as to be unable to stand at all without the aid of a support which it has been the practice to attach them to.

Now, the object of the present invention 25 is to provide a practically flat or plane toy figure, which, while being light in construction, will at the same time possess the necessary inherent stability to be self-supporting, be neat, compact and attractive, 30 and inexpensive to manufacture.

In the accompanying drawings:—Figure 1 is a front elevation of a toy figure, constructed according to the present invention, the body portion being made to represent a little girl. Fig. 2 is a view taken 35 at a right angle to Fig. 1. Fig. 3 is a plan of one of the feet of the toy figure shown separately. Fig. 4 is a vertical section taken on the line 1—1 of Fig. 3. Fig. 5 is a side 40 elevation of a modified device in which the body portion of the toy figure is made to represent a giraffe, and Fig. 6 is a front elevation of one of the feet separately.

In the several figures of the drawings, 45 like parts are indicated by similar letters of reference.

In the drawings, *a* represents the body portion, *b* the legs, and *c* the feet of the toy figure.

50 Referring to Figs. 1 to 4, the body portion *a* of the figure is made of cardboard, two-ply wood or other light or thin material of sufficient toughness, while the legs *b* and feet *c* of the figure are made comparatively heavier so that the figure will possess

the necessary stability to enable it to stand upright without the aid of extraneous supports.

As shown in the drawings, the legs *b* preferably take the form of spindles and may be constructed, for example, of wood so as to be comparatively heavier than the body *a*.

The legs *b* are articulated or jointed to the body *a* of the figure, a slot *b'* being formed in each of the legs *b* at the upper end thereof, and into which slots the lower edge *a'* of the body portion *a* of the figure fits. Suitable pivotal connections, such as pins *b''*, are then passed through perforations in the parts to connect them together in a manner to permit of movement. Or, the legs *b* and body portion *a* of the figure may be joined together in any other suitable way which will permit of the movement of said parts with relation to each other.

The feet *c* are made of such a size as to provide sufficient base for the figure to stand upon and are jointed to the legs *b* in 80 any suitable manner which will permit of variation in their angular position. One method of so jointing the feet *c* to the legs *b* is to form a socket like recess *c'* in each of the feet *c* into which the reduced lower ends 85 *b''* of the legs *b*, loosely fit, as shown in the drawings said lower ends being circular in cross section to admit of the angular movement of the feet *c*. A circular groove or slot *b''* is formed in the lower ends *b''* of each 90 of the legs *b* with which engage screw pins *c''* or the like passed through the feet *c*. The legs *b* and feet *c* are thus held together in such manner as will permit of angular variation between said parts.

The figures may be made of a comparatively large size, preferably life size, and may be provided with cards or the like on which may be printed or otherwise marked any suitable distinguishing reading matter. 100 For example, when the figure represents a little boy or girl, it may illustrate a character in a nursery rhyme or the like and its attached card may bear an inscription applicable to the character represented.

The figure may be constructed to represent any human being, or any member of the lower animal world. At Fig. 5 an example of the latter is shown which represents a giraffe. In this case the feet *c* are pref- 110

erably modified in shape, as shown in Fig. 6, in order to afford a sufficient base to give to the figure the required stability.

The figures may be packed and sold in boxes, each containing any convenient number which may represent, for example, a number of little boys or girls, constituting the members of a school, a troupe of boy scouts, the characters in a rime or fairy tale 10 or otherwise as desired.

The body portion *a* may have the pictorial representation of the figure it is intended to indicate marked thereon in any well known manner.

15 By the means hereinbefore described, a toy figure, preferably large or life size, will be obtained which although light, portable and compact in construction, will at the same time possess inherent stability, and be 20 neat, attractive, inexpensive to manufacture and be instructive and amusing to children.

Having now particularly described and ascertained the nature of the said invention and in what manner the same is to be performed I declare that what I claim is:—

25 1. In a toy figure the combination of a flat body portion of thin material, round

legs of comparatively heavy material pinned to the body and feet of heavy material jointed to the legs in such manner as 30 to be capable of being turned to any desired angle as set forth.

2. In a toy figure the combination of a flat body portion of thin material, round legs of heavier material and of considerably larger 35 diameter than the thickness of the body and slotted at their upper ends to receive the lower part of the body, pins crossing the slots and pivotally connecting the legs with the body and heavy feet mounted on the 40 lower extremities of the legs with capability of rotation in a horizontal plane as set forth.

3. In a toy figure the combination of a flat body portion of thin material, round legs of comparatively heavy material pinned to the body and at their lower extremities formed of reduced diameter, feet of heavy material bored to receive the reduced portions of the legs, circular grooves in said reduced portions and pins carried by 45 50 the feet engaging said grooves so that the feet are capable of rotation as set forth.

JOHN WILKS.
